FIG. 6.

UNITED STATES PATENT OFFICE.

OSCAR B. SCHELLBERG, OF NEW YORK, N. Y.

CORK-RETAINER.

1,081,777.

Specification of Letters Patent. Patented Dec. 16, 1913.

Application filed September 24, 1912. Serial No. 722,041.

To all whom it may concern:

Be it known that I, OSCAR B. SCHELLBERG, a citizen of the United States, and a resident of the city of New York, borough of the Bronx, in the county and State of New York, have invented a new and Improved Cork-Retainer, of which the following is a full, clear, and exact description.

The subject matter of this application is 10 a new and improved cork retainer herein-after referred to broadly as a corker.

Many devices have heretofore been provided for the purpose of preventing the accidental removal of corks from bottles due 15 to the formation of gas or other causes, all of such devices, however, possessing certain disadvantages which it is the purpose of the present invention to overcome.

The invention shown is comprehended in 20 an integral structure which is characterized by the absence of sharp angles where the different portions adjoin, the structure being further characterized by a gradual curvature between portions extending angularly with respect to each other, whereby in 25 the handling which the device must receive in use the tendency of damage is materially lessened. The structure disclosed is also characterized by non-uniformity of cross 30 sectional area, since it has been ascertained that certain portions of less cross sectional area will at the same time fully perform the purpose for which they are intended, such characterization resulting in lessening 35 the cost of production.

Reference is to be had to the accompanying drawings forming a part of this specification, in which like characters of reference indicate corresponding parts in all the 40 views, and in which—

Figure 1 is an end view of the device in position on the neck of a bottle; Fig. 2 is a side view; Fig. 3 is a plan view of the device; Fig. 4 is an end view thereof, while 45 Fig. 5 is a side view.

Any suitable bottle or equivalent vessel is designated 1 and is shown provided with the usual peripheral shoulder 2 adjacent the upper end of the neck; a cork 3 which may 50 be of any desired material is shown closing the neck of the vessel.

The cork-retainer is preferably of integral construction and made of rubber or elastic material, and comprises a circular base 4 and an arch 5 extending therefrom. The base 4 is of annular construction, the inner

diameter being such that the device may be closely engaged on the outside of the neck of the vessel, the outer diameter of the base being substantially equal to the diameter of the shoulder, as shown particularly in Fig. 1, whereby the said base 4, to an extent, protects the shoulder from injury. The thickness of the base 4 will, of course, depend upon the size of the bottle with which 60 the device is employed, and to an extent upon the material contained within the bottle.

Referring particularly to Figs. 1, 3 and 5, it will be noted that the arch 5 is made 70 up of the vertically extending sides 6 and the top portion 7 of reduced cross sectional area, the thickness of the sides 6 increasing from the said top portion as the base 4 is approached; the sides 6 at about an intermediate portion are bifurcated, whereby the divergent ends 8 result, which ends are separated by an opening 9, it being noted that the sides 6, ends 8 and base 4 merge one into the other without any abrupt corners 75 or angles.

Referring particularly to Figs. 2 and 5 it will be noted that the top portion 7 of the arch is of less thickness than the sides 6, the purpose of such construction being 85 this:—After the article has been positioned on the neck of the bottle by being slipped over the shoulder 2, the cork 3 is inserted, the arch 5 being drawn to one side to permit this, the arch being then manipulated in 90 order to stretch it a certain amount and place it over the top of the cork, as shown in Figs. 1 and 2; the top of the cork being substantially flat any movement of the cork relatively to the bottle will cause lengthening or 95 shortening of the sides 6 of the arch, the top portion 7 remaining substantially immovable as far as stretching is concerned, due to the fact that the top of the cork closely engages the under side of this top 100 of the arch, thereby preventing movement of one relatively to the other, which is necessary in the stretching process.

The device is preferably molded from a single piece of material, and the size thereof 105 may be varied; in fact, the invention may be comprehended in articles of widely different sizes in order to be used on bottles of different dimensions.

The manner of using the article has been 110 set forth in describing the structure; such manner of use provides a simple and im-

proved means for preventing accidental removal of the cork.

The gradual increase in thickness of the sides 6 as they extend toward the base 4 is for the purpose of increasing the tension upon the cork, so as to draw it into the neck of the bottle. Since the base 4 is under the flange or shoulder 2 at the end of the neck of the bottle, the result is that the cork will 10 naturally be pulled down. The openings 9 are to permit the uniform stretching of the base 4, as well as the uniform separation of the lower ends 8 of the sides 6, so as to prevent the arch 5 from slipping off the cork. 15 These openings will allow the sides 6 and their diverging ends 8, together with the base 4, to adjust themselves in accordance with the size of the bottle and cork; as the ends 8 are stretched apart the top 7 of the 20 arch 5 tends to force the cork into the mouth of the bottle. The relatively thin top portion 7 gives an important result in that, when stretched over the cork top, it presents very little vertical projection such as might 25 be accidentally engaged at the side edges in contacting with other bodies. Moreover, any accidental contact or blow on the side edges of the reduced portion will not displace the retainer, because the effect of any 30 blow is necessarily localized, whereas with a thick top portion, the arch, in practice, is liable to be pushed sidewise from its position by contact with another object. The branching of the arch in the form of sepa- 35 rate arms 6 that form with the base ring 4, the opening 9, produces two important results, to wit: with the retainer in place, the bead or shoulder 2 of the neck at the opening 9 extends into the latter, and the under 40 side of the shoulder 2 overlies the bottom wall 9^a of the opening, and thus there is a positive engagement between the retainer and bottle neck by opposed shoulders directly on the median line of the arch, which 45 resists both the tendency of displacement of the arch by slipping sidewise, and the tilting of the cork by a lateral pressure. Fur-

thermore, the diverging arms 6, it will be seen, act as inclined braces in both directions at opposite sides of the median line of the arch, to resist the transverse slipping of the arch or the tilting of the cork. Finally, the diverging arms produce a broadened base for the arch, free from angles, which prevents tearing and separation when the retainer is stretched over the bottle and cork; tearing frequently happens with retainers having the side edges of the arch rising approximately straight from the base ring. The thickening of the arch at the base also, 55 contributes to the prevention of tearing.

I wish to have it understood that the above description is illustrative only, disclosing but one embodiment of my invention, and that I do not care to be limited to 60 the exact details shown and described, but reserve to myself the right to make whatever changes in the shape, size and arrangement of the parts fairly fall within the scope and spirit of my invention.

Having thus described my invention, what I claim as new and desire to secure by Letters Patent is:—

A resilient retainer for corks, comprising a base ring adapted to encircle a bottle neck 75 below the usual exterior bead thereof, and an arch having the sides joining the base rings by diverging arms presenting diametrically opposite openings between the arms at the base of the arch, in which openings opposite portions of the said bead may enter, the openings being surrounded on all sides by the material of the retainer and presenting lower walls forming shoulders to engage under the shoulder of the bead, and 80 the arms forming resistance members at the sides of the arch.

In testimony whereof I have signed my name to this specification in the presence of two subscribing witnesses.

OSCAR B. SCHELLBERG.
